To all whom it may concern:

Be it known that I, HORACE C. WILCOX, of West Meriden, in the county of New Haven and State of Connecticut, have invented a new Design for Tea-Bell; and I do hereby declare the following, when taken in connection with the accompanying photographic illustration, to be a full, clear, and exact description of the same, and which said illustration constitutes part of this specification and represents a side view.

This invention relates to a design for tea-bell, with special reference to the handle of the bell; and consists in the arrangement of a goat, chamois, or other animal of like character, in the position as fully shown in the accompanying photographic illustration.

The bell, being no part of this design, may be of any form, according to the taste of the manufacturer or demands of the trade.

On the bell at the top is represented a rocky surface, and upon this is arranged the figure of a goat, chamois, or other animal of like character, in the position of having landed from a leap upon the said rocky surface, as fully shown in the accompanying photographic illustration.

I claim as my invention—

The design for tea-bell, as shown in the accompanying photographic illustration and as herein described.
